INVENTOR.

James M. Ide

UNITED STATES PATENT OFFICE.

JAMES M. IDE, OF TROY, NEW YORK, ASSIGNOR TO GEO. P. IDE, BRUCE & CO.,
OF SAME PLACE.

COLLAR.

SPECIFICATION forming part of Letters Patent No. 279,567, dated June 19, 1883.

Application filed May 4, 1883. (No model.)

To all whom it may concern:

Be it known that I, JAMES M. IDE, a citizen of the United States of America, and residing in the city of Troy, in the county of 5 Rensselaer and State of New York, have invented certain new and useful Improvements in Collars, of which the following is a specification, reference being had to the accompanying drawings.

10 My invention relates to improvements in such collars as are commonly worn by ladies, and have flaring capes shaped to conform to the chest around the neck of the wearer. In such collars heretofore made the cape commonly 15 consists of only one ply or thickness of muslin, and is of uniform thickness from its inner edge, where it is stitched to the body of the collar, to its bound or hemmed outer edge. In washing, starching, and ironing such collars the flaring cape, of a single or uniform 20 thickness from its inner to its outer edge, is very liable to be torn through along the body of the collar; and in wearing such collars the thinness and pliability of the cape along the 25 body of the collar prevents the cape from properly controlling the position and adjustment of the collar on and around the neck, and causes the cape to soon become crumpled and broken along the collar-body.

30 To cheaply overcome or lessen the aforesaid defect is a primary object of my invention, and I accomplish that object by making an inner portion of the cape along the collar-body thicker, stronger, and of greater stiffness 35 than the outer portion of the cape, substantially as hereinafter set forth.

In the aforesaid drawings, Figure 1 is a view of a collar which embodies one form of my invention, and Fig. 2 represents an expanded 40 section of the same at about the line *z z* in Fig. 1. Fig. 3 is a view of a collar that embraces portions of the same invention, and Fig. 4 is an expanded section of the same collar at about the line *y y* in Fig. 3.

45 A is the body of the collar, and B is the cape, which is continuous in Fig. 1, but is in three segments in Fig. 3. In each of the collars the inner portion, C, of the cape is of greater thickness, strength, and stiffness than 50 its outer portion, D. It is important that the outer portion, D, of the cape shall be quite

thin and flexible, so that while the collar is being worn the outer portion of the cape shall freely bend between and conform to the inner and outer garments around the neck of the 55 person. I make the inner portion, C, of the cape of greater thickness, strength, and stiffness than the outer portion, D, in order to lessen or prevent the tearing of the cape along the collar-body in washing, starching, and 60 ironing the collar, and in order that, while the starched and ironed collar is being worn, the inner portion of the cape, by its great thickness, strength, and stiffness, shall greatly lessen or prevent the crumpling and breaking 65 of the cape along the collar-body, and shall materially assist in adjusting and retaining the collar-body in proper position around and upon the neck of the person, and may present a smooth and comely appearance when worn 70 exposed to view.

As regards this improvement of having the inner portion of the cape of greater thickness, strength, and stiffness than its main outer portion, the cape may extend along the whole 75 length of the collar-body, as in Fig. 1, or may be in segments, as shown in Fig. 3, or may extend and have its thickest inner part, C, of various widths and lengths along only a sufficient portion of the lower edge of the collar-body to accomplish the aforesaid object. I commonly have the thicker inner portion, C, of the cape extend to or nearly to or somewhat beyond the front end parts of the collar-body, and make in such thickened inner end 80 parts of the cape button-holes *e e*, adapted to receive a connecting stud or button, and thereby assist the thick inner portion of the cape in adjusting and retaining the collar in proper position upon and around the neck of the 85 wearer; and in such cases the thickened inner portion of the cape may be extended outward various distances, or across the ends of the cape, as indicated by dotted lines at *x x* in Fig. 3. 95

The inner portion, C, of the cape can be made thicker, stronger, and of greater stiffness than the main outer part, D, by having the outer part consist of only one ply of muslin, and the inner portion consist of one ply of very 100 thick linen, cotton, or compound linen and cotton fabric; but I generally prefer to have the

inner part, C, of the cape composed of two or more plies of cotton or linen and cotton fabrics, and the outer portion, D, of only one ply, as indicated in Fig. 2 or 4.

5 In making an inner portion of the cape of a collar thicker, stronger, and of greater stiffness than the outer portion, I consider that it is generally best to have one main ply, f, Figs.

10 and 2, extend from the inner edge to the outer edge of the cape, and a smaller re-enforcing ply, g, stitched along its outer edge, h, to and upon said main ply, and secured along its inner edge with said main ply to the body of the collar, substantially as illustrated by Figs.

15 1 and 2.

What I claim as my invention is—

1. A collar having a cape, B, of which an inner part, C, that extends along and is secured to the body of the collar, has greater 20 thickness, strength, and stiffness than the main outer portion, D, of the cape, as set forth.

2. A collar having a cape, of which the forward inner parts that extend along and are united to the end portions of the body of the collar are thicker and stronger than the main outer portion of the cape, and have button-holes e e therein, as described.

3. A collar having a cape composed of a main ply, f, and a smaller re-enforcing ply, g, stitched along its outer edge, h, to and upon 30 said main ply, and secured along its inner edge with said main ply to the body of the collar, as set forth.

In testimony whereof I hereunto set my hand, in the presence of two subscribing witnesses, 35 this 2d day of May, 1883.

JAMES M. IDE.
